UNITED STATES PATENT OFFICE.

GEORGE W. GRASER, OF BEAVER FALLS, PENNSYLVANIA, ASSIGNOR TO KOPPEL INDUSTRIAL CAR AND EQUIPMENT COMPANY, OF PITTSBURGH, PENNSYLVANIA, A CORPORATION OF PENNSYLVANIA.

STAKE-RELEASING POCKET.

Application filed August 26, 1924. Serial No. 734,250.

This invention relates to cars and more particularly to sugar cane or like cars, and has for an object the provision of a stake pocket by which a stake of the car may be 5 readily released without lifting it vertically from the pocket.

Another object of the invention is to provide, in a stake pocket, a novel locking and releasing means for the stake.

10 These and other objects will be apparent from the following description.

Referring to the drawing in which like reference characters refer to like parts, Fig. 1 is a side elevational view of a portion of a car embodying the invention; Fig. 2 is a 15 sectional view of the same taken on the line 2—2 of Fig. 1, showing the side stake in locked position in full lines and in unlocked position in dashed lines; and Fig. 3 is a similar sectional view showing the stake released.

Referring now in detail to the drawing, the reference character 1 indicates the side sill of a car and 2 the floor of the car which floor is secured to the side sill. At intervals 25 throughout the length of the side sill stake pockets 3 are provided, each of which is secured to the side sill and are each adapted to receive the lower portion of a stake 4.

Each of the stake pockets 3 is provided 30 with spaced sides 5, back 6, and bottom 7, all of which are preferably integral, and is further provided with a front or door 8 which extends between and is pivotally connected with spaced lugs 9 on the bottom 7 through the medium of a pin or bolt 10. Adjacent its upper edge the door 8 is provided with outwardly projecting spaced lugs 11 in which a pin or bolt 12 is mounted. This bolt passes through and beyond each 40 of the lugs 11 and on each of the ends of the bolt which projects beyond the adjacent lug 11, one leg of a U-shaped lever 13 is operatively mounted. This lever is provided with spaced cam portions 14 which are preferably integral with the legs of the lever and are adapted to engage by means of the cam surfaces 15 with cam surfaces 16^a formed on extensions or projections 16 of the sides 5 to lock the door 8 and thus form a stake

50 pocket which will hold the stake in its proper upright position.

Assuming a car is equipped with the invention and loaded with cane, and it is desired to unload it, an operator moves the lever 13 in the direction as indicated by the 55 arrow in Fig. 2, causing the cam portions 14 to be moved free of the projections 16, as shown in dot and dash lines, at which time the pressure of the load against the stake will cause the door 8 to drop downwardly to the position as shown in Fig. 3, thus freeing the stake and permitting it to drop outwardly and so that the lading is permitted to dump at the side of the track. Now, when it is desired to mount the stake 60 65

the operator raises the door 8 until it is in its closed position, and then manipulates the lever 13 in such a manner that the cam

surfaces 15 engage with the cam surfaces 16^a on the projections 16, thus locking the 70

door 8 in closed position. The operator now 75

lowers the stake into the pocket formed by the sides 5, back 6, bottom 7, and door 8,

where it is held against outward movement

until it is again desired to unload the car. 75

Having thus described the invention, what I claim as new and desire to secure by Letters Patent is:—

1. A stake pocket having a rigid part, a part hinged to said rigid part to swing 80 downwardly, a lug on said rigid part, and a member rotatably mounted on said hinged part adapted to engage said lug to lock said hinged part.

2. A stake pocket having a rigid part, a 85 hinged part adapted to swing downwardly, a lug on said rigid part, and means on said hinged part adapted to engage said lug to lock said hinged part in closed position.

3. A stake pocket having a rigid part, a 90 hinged part adapted to swing downwardly, a lug on said rigid part, and a cam on said hinged part movable into and out of locking engagement with said lug.

4. A stake pocket having a rigid part, 95 lugs on each side of said rigid part, a hinged part, a cam at each side of said hinged part movable into and out of locking engagement

with said lugs, and a lever for operating said cams.

5. A stake pocket having a hinged door, lugs on each side of said pocket adjacent 5 said door, and cams mounted on said door adapted to be moved into and out of locking engagement with said lugs.

6. A stake pocket having a hinged door,

lugs on said pocket adjacent said door, members mounted on said door and movable into 10 and out of locking engagement with said lugs and a U-shaped lever for operating said members.

In testimony whereof I affix my signature.

GEORGE W. GRASER.
